ABSTRACT: This invention is concerned with means for controlling the flow of liquid through a drop pipe into a vessel comprising a valve movable between a closed position in which the liquid can flow at a limited rate only and an open position in which the liquid can flow at a higher rate, a releasable locking device normally preventing movement of the valve from the closed to the open position, a pneumatic operating chamber, means responsive to the pressure in the operating chamber for releasing the locking device, a relief passage communicating with the operating chamber and having an opening adjacent the delivery outlet of the drop pipe, thereby maintaining the pressure in the operating chamber substantially normal until the said opening is blocked by the rise of liquid level in the vessel, and means for applying a pressure differing from that of the atmosphere to the operating chamber, whereby upon said opening becoming blocked said nonatmospheric pressure is established in the operating chamber and the locking device is released.

FIG.3

INVENTOR.
WILLIAM FRANK JUDD

LIQUID FLOW CONTROL VALVES

When discharging highly inflammable liquids through a drop pipe into a tanker, static electricity can be generated with consequent risk of explosion or fire. The buildup of electrical charges is dependent on the velocity of discharge of the liquid from the drop pipe and on the contents or residue in the tank at the time of fill. In order to minimize the risk, it has been recommended that the rate of discharge should be limited (to approximately 70 gallons per minute for a 3-inch pipe and approximately 120 gallons per minute for a 4-inch pipe) until the end of the drop pipe has been completely submerged in the liquid. The present invention provides liquid flow control means adapted to ensure compliance with such a recommendation.

In accordance with the present invention, means for controlling the flow of liquid through a drop pipe into a tanker or other vessel comprise a valve movable between a closed position in which the liquid can flow at a limited rate only and an open position in which the liquid can flow at a higher rate, a releasable locking device normally preventing movement of the valve from the closed to the open position, a pneumatic operating chamber, means responsive to the pressure in the operating chamber for releasing the locking device, a relief passage communicating with the operating chamber and having an opening adjacent the delivery outlet of the drop pipe, thereby maintaining the pressure in the operating chamber substantially normal until the said opening is blocked by the rise of liquid level in the vessel, and means for applying a pressure differing from that of the atmosphere to the operating chamber, whereby upon said opening becoming blocked said nonatmospheric pressure is established in the operating chamber and the locking device is released.

The passage through which the liquid can flow at a limited rate may be permanently open, the starting and ending of the delivery flow being controlled by means of any suitable construction disposed on the upstream side of the valve above referred to, and this valve may be moved automatically to its open position by the pressure of the liquid being delivered when the locking device is released to permit such movement, biasing means being provided to return the valve to its closed position when the delivery flow is stopped.

In an alternative arrangement, the passage through which liquid flows at a limited rate when the valve is closed is controlled by a second valve, biased to closed position, and operating means are provided, manually movable to open the second valve and on further movement to open the first valve, which is also biased to closed position.

Two particular embodiments of the invention are further described below, by way of illustrative example, with reference to the accompanying drawings, in which:

FIG. 1 is an axial section through one form of liquid flow control means and the drop pipe through which the liquid is delivered,

FIG. 2 is a similar axial section through an alternative form of control means,

FIG. 3 is a diagrammatic view of a modification of FIG. 2.

Referring first to FIG. 1, the valve illustrated comprises a main body 1, to which is secured a flange 2, adapted for connection to a liquid supply pipe. A resilient disc 3 makes a liquid-tight seal between the parts 1 and 2 and forms a seating for a valve plunger 4. The plunger 4 is secured on a stem 5, which is slidably guided in the parts 1 and 2, the plunger assembly being urged into the closed position illustrated by a spring 6.

The plunger 4 is formed with passages 7 which (when the plunger is in the closed position) permit liquid to flow at a limited rate from the inlet into the interior 8 of the body. The space 8 is in open communication with a drop pipe 9, connected at one end to the body by a flange 10 and provided at its other end with a deflector spout 11.

The valve stem 5 is formed with passages 12, which connect the liquid flow passages 7 to a chamber 13 formed in the body and bounded on its outer side by an annular diaphragm 14, the chamber being sealed fluidtight by an O-ring 15 surrounding the valve stem 5. The diaphragm 14 is secured at its outer periphery between the body 1 and a cap 16, while its inner periphery is secured to the cap 1 by a tubular member 17. A spring 18 acts on a locking sleeve 19 secured to the diaphragm 14 to urge those parts into the positions illustrated. The locking sleeve 19 has two parts of different diameters. When in the position illustrated, the part of smaller diameter holds a number of loose balls 20 engaged between a shoulder on the valve stem 5 and the stationary abutment constituted by member 17, thus preventing the stem from moving against the action of spring 6. The chamber 13 is connected through a passageway 21 to an opening 22 provided in the delivery spout 11.

When liquid is delivered to the inlet, it flows at a restricted rate through the passages 7 in the valve plunger and is discharged through the drop pipe 9 and spout 11. The venturi effect of the flow of liquid through passages 7 causes a reduction in the pressure existing in passages 12 and chamber 13, but so long as the passage 21 remains open, the pressure reduction in chamber 13 is insufficient to cause movement of the diaphragm 14. When the liquid level in the tanker or other receiving vessel has risen sufficiently to obstruct the open end 22 of passage 21, the pressure in chamber 13 is substantially reduced by the suction applied through passages 12 and diaphragm 14 moves against the action of spring 18, the movement of sleeve 19 permitting outward movement of the balls 20. The pressure of the incoming liquid on valve plunger 4 then overcomes the action of spring 6 and moves the valve member off its seating 3, allowing liquid to flow to the drop pipe at an increased rate. When the delivery of liquid ceases, spring 6 automatically returns the valve plunger assembly to the closed position shown, and the pressure in chamber 13 reverts to normal, so that spring 18 returns the sleeve 19 to the locking position shown. The apparatus is then ready for the next operation of the valve.

Referring now to FIG. 2, the modified valve illustrated comprises a main body 31, having a liquid inlet passage 32 and an outlet passage 33, the latter communicating with a drop pipe 9 similar to that shown in FIG. 1. A port connecting passages 32 and 33 is normally closed by a valve disc 34 carried by a valve plunger 35, slidably and sealingly guided in the body 31 and urged downwardly by a spring 36. The upper end of the body 31 is closed by a member 37, against which the spring 36 abuts, and a cap 38, members 37 and 38 clamping between them a flexible diaphragm 39. The diaphragm is secured at its center to a shouldered tubular member 40, which is slidably and sealingly engaged with a tubular extension 41 of the cap 38.

A liquid passage 42 extends through the main valve plunger 35 and is normally closed by a valve disc 43 carried on a stem 44 which is urged downwardly by a spring 45. The lower end of spring 36 and the upper end of spring 45 abut against a stem 46, which carries at its lower end a valve 47 normally closing a port connecting liquid passage 42 to the upper side of main valve plunger 35. The stem 46 passes slidably and sealingly through the member 37 and its shaped upper end engages a number of loose balls 48, which are trapped between the parts 40, 41 and 46. A downward extension of the stem of valve 43 carries a roller 49, adapted to be engaged by a cam arm 50, which is turned clockwise to effect opening movement of the valve.

The liquid flow passage 42 controlled by valve 43 is so shaped as to produce a venturi effect when liquid flows through it and create partial vacuum in a passage 51, formed in the main valve plunger. Passage 51 communicates through a tube 52 with the chamber 53 on the lower side of diaphragm 39. Also communicating with this chamber is a tube 54 which extends along the drop pipe through which liquid is delivered and terminates at a suitable point adjacent the end of that pipe, the end of tube 54 being open.

The drawing shows the parts in the closed position of the valve. To start liquid flow, arm 50 is manually turned clockwise, thereby lifting valve 43 and allowing liquid to flow from inlet 32 to outlet 33 through the passage 42. Upward movement of stem 44 of valve 43 is arrested when a shoulder on this stem engages the lower end of the stem 46, upward movement of stem 46 being prevented by the blocking action of balls 48. The liquid flow through passage 42 applies suction to the passage 51 and thus tends to reduce the pressure in chamber 53. However, so long as the end of tube 54 remains open, the pressure in chamber 53 is not substantially reduced and diaphragm 39 continues to be held in the position shown by the spring 55, so that member 40 carried by the diaphragm continues to hold the balls 48 in locking position. Turning movement of operating cam 50 is thus limited to that required to effect full opening of valve 43, which allows the delivery of liquid to the drop pipe at the safe limited flow rate. When the level of the delivered liquid has risen sufficiently to close the open end of tube 54, so that it becomes safe to deliver liquid at a higher flow rate, the continued application of suction to passage 51 reduces the pressure in chamber 53 and the diaphragm 39 moves downwardly against the action of spring 55. The resultant downward movement of member 40 provides space for the outward displacement of balls 48, so that stem 46 is no longer locked against upward movement. Continued clockwise rotation of cam lever 50 now causes the stem 44 of the first stage valve 43 to raise stem 46 relative to the main valve plunger 35, thus opening valve 47 and equalizing the pressure on the two sides of the plunger 35. Still further movement of lever 50 raises the plunger 35 and opens the main valve 34, permitting liquid to flow at a high delivery rate. The valve can be kept fully open for as long as required, either by continuing the manual pressure on lever 50, or by means of a suitable stay-open device. When lever 50 is returned, or permitted to return, anticlockwise, all the valve parts are returned to their starting positions by the springs and the balls 48 return to the locking position.

The tube 52 is shown as being of telescopic construction, but any other arrangement which will afford a suction connection between passage 51 and chamber 53 while allowing movement of the main valve plunger 35 can be adopted.

Many other modifications are possible in each of the constructions illustrated, these constructions being shown and described by way of example only. No attempt will be made to set out all the modifications possible, but some of them are briefly noted below.

The passage whose closure allows the pressure in the diaphragm chamber to be reduced, thus permitting opening of the main valve can be provided with a normally open branch, for example branch 54 shown in FIG. 2 which is closed, (for example by means of a suitable solenoid device 57, only when the receiving tank into which the drop pipe delivers has been properly earthed or grounded, thus ensuring that delivery at the increased rate will not commence until that operation has been performed. When the tank has been properly grounded a signal is transmitted along 58 to the device 57 to cause the device to close branch 56. Instead of using suction to produce a subatmospheric pressure in the chamber on one side of the diaphragm, air under superatmospheric pressure may be supplied for example by a conduit 60, FIG. 3 from any suitable

source 59 to the chamber on the opposite side of the diaphragm 39, the relief passage being also connected to that chamber so that the pressure in it does not rise appreciably until the liquid in the receiving vessel has reached the required level.

I claim:

1. Means for controlling the flow of liquid through a drop pipe into a vessel comprising a valve movable between a closed position in which the liquid can flow at a limited rate 10 and an open position in which the liquid can flow at a higher rate, a releasable locking device normally locking the valve in its closed position, a pneumatic operating chamber, means responsive to the pressure in the operating chamber for releasing the locking device to allow the valve to move to its open position, a relief passage communicating with the operating chamber and having an opening adjacent the delivery outlet of the drop pipe, thereby maintaining the pressure in the operating chamber substantially normal until the said opening is blocked by the rise of liquid level in the vessel, 20 and means for applying a pressure differing from that of the atmosphere to the operating chamber, whereby upon said opening becoming blocked said nonatmospheric pressure is established in the operating chamber and the locking device is released.
2. Means in accordance with claim 1 in which the passage through which liquid flows at a limited rate when the valve is closed is so shaped as to produce a venturi effect and apply a pressure below that of the atmosphere to the control chamber.
3. Means in accordance with claim 1 in which the means responsive to the pressure in the operating chamber is a flexible diaphragm constituting a wall of the chamber, release of the locking device being effected by movement of the diaphragm.
4. Means in accordance with claim 1 in which the releasable locking device comprises a rod which moves longitudinally upon opening and closing movement of the valve and has a shoulder formed thereon, a stationary abutment spaced axially away from the shoulder, a sleeve coaxially surrounding the rod and movable axially in response to a change of pressure in the control chamber, the sleeve having portions of smaller and larger diameter, and a plurality of free balls disposed in the annular space between the rod and the sleeve, the smaller diameter portion of the sleeve normally holding the balls trapped between the shoulder on the rod and the stationary abutment to prevent axial movement of the rod.
5. Means in accordance with claim 1 in which the passage through which liquid flows at a limited rate when the valve is closed is controlled by a second valve, biased to closed position, and operating means are provided, manually movable to open the second valve and on further movement to open the first valve, which is also biased to closed position.
6. Means in accordance with claim 5 in which the second valve is movable beyond the position at which it is fully open to engage and open the first valve, the locking device preventing such further movement of the second valve until released.
7. Means in accordance with claim 1 in which the passage through which the liquid flows at a limited rate is permanently open and the valve is biased to closed position but is adapted to move to open position (upon release of the locking device) 60 in response to the pressure of the liquid thereon.
